MUFFLER FOR INTERNAL COMBUSTION ENGINES

Filed Aug. 5, 1929

INVENTOR
Edward H. Radecky.
BY *James Dickey, Inc.*

ATTORNEY

UNITED STATES PATENT OFFICE

EDWARD H. RADECKY, OF DETROIT, MICHIGAN, ASSIGNOR TO THE MURRAY CORPORATION OF AMERICA, A CORPORATION OF DELAWARE

MUFFLER FOR INTERNAL COMBUSTION ENGINES

Application filed August 5, 1929. Serial No. 383,464.

My invention relates to mufflers for internal combustion engines and has for its object to provide a simply and cheaply constructed and efficient device. The practice 5 heretofore has been to complicate such devices by a multitude of parts and complication of arrangement to such an extent that they are relatively expensive and difficult to manufacture. I have found by experience 10 that the simple device hereinafter described will operate with the required efficiency and may be more cheaply and easily produced than the kind of devices now in common use.

In the drawing,

15 Fig. 1 is an elevational view, partly in section, of my device.

Fig. 2 is a view taken on line 2—2 of Fig. 1.

Fig. 3 is an end view.

20 Every form of the novel muffler unit may comprise two concentric tubes, preferably cylindrical and of unequal length—the outer tube being designated by the numeral 10 and the inner tube by the numeral 11. 25 Two identical but oppositely disposed end pieces, each comprising a single stamping, are preferably provided, the forward end piece being designated by the numeral 12 and the rear one by the numeral 13. The end pieces are preferably conical in general 30 shape; and they may be formed with concentric shoulders serving both for the purpose of adding strength to the unit and for the purpose of providing oppositely deflected flanges which make convenient points of attachment for the tubes 10 and 11. The tube 10 may be welded, as at 14, to the outer shoulder of each end piece; and the tube 11, shown 35 as shorter, may be similarly welded, as at 15, to the inner shoulder of each end piece. An entrance pipe 16 is shown as so proportioned as both to fit the exhaust pipe of an engine and to be secured within tube 11. For example, it may have one end welded, as at 17, in the central opening in the end piece 12; and an oppositely disposed tail piece 18, if provided, may be identical in form and may have one end welded, as at 19, in the central 40 opening in the end piece 13,—to receive which

the inner ends of inner flange of the end stamping may be inwardly offset.

Intermediate the ends of the inner tube 11 there may be positioned a cup-shaped baffle plate 21, which divides the tube 11 into two 55 chambers, preferably unequal in length. The baffle 21 is shown as provided with a lateral marginal flange which snugly interfits with, and may be suitably secured to, the inner surface of the inner tube. A second 60 but apertured baffle plate 22 is shown as similarly positioned intermediate the ends of the tube 10 and at a point opposite the baffle 21. The illustrated baffle 22 has a central opening which permits a slidable insertion of the tube 11; and it has a lateral 65 marginal flange, around this opening, which is secured to the outer surface of the tube 11 opposite the point at which the baffle 21 is secured to the inner surface thereof. The 70 outer edge of the baffle 22 is formed with a lateral flange which interfits with and may be secured to the inner surface of the tube 10; and the inner tube 11 is shown as apertured in its respective end portions. 75

Those portions of the tubes 10 and 11 to the left of the substantially co-planar flanged baffles 21 and 22 are hereinafter referred to as providing an expansion compartment; and they are preferably of greater capacity, by 80 reason of greater length, than those portions providing a cushioning compartment to the right of the baffles; but the sizes of these compartments, each comprising a single inner chamber and a single outer chamber, may 85 be varied to suit conditions, and that part of the tube 11 which thus subdivides the expansion or inlet compartment, to the left of the baffle 21, is preferably provided with a plurality of groups of apertures. For example one group may be arranged adjacent the baffle 21 and another group arranged adjacent a connection element serving as an inlet pipe; and that part of the tube 11 which subdivides the cushioning or outlet compartment to the right of the baffle 21 may be provided with a plurality of apertures uniformly 90 arranged in a single group about the tube and between the baffle 21 and an oppositely disposed connecting element in the form of 95 100

outlet pipe 18,—shown as identical in form with pipe 16.

In operation, the gas passes into the inlet pipe 16, as indicated by arrows; and some of it passes through the apertures adjacent the left end of the pipe 11; and the remainder either passes through the apertures adjacent the baffle 21 directly or is reflected from the baffle 21 and then passes through the adjacent apertures. The gas passes from the left end of the tube 11 laterally into the left end of the tube 10 and rearwardly through the apertured baffle 22 into the right end of the tube 10, then into the right end of the tube 11 through the apertures in the tube 11 to the right of the baffle 21 and out through the outlet pipe 18. The gas, expanding into the left outer chamber of the tube 10, then comes in contact with the walls of the tube, which are cooled by the outside air and tend to condense the gas. This tendency continues during the time the gas remains in either compartment of the tube 10.

Preferably the total area of the lateral apertures in the right end of the tube 11, and the total capacity of both tubes (together constituting the cushioning or outlet compartment) to the right of the baffles 21 and 22, are less than the total area of the lateral apertures in the tube 11 to the left of the baffle 21, and the capacity of the tubes 10 and 11 (together constituting the expansion or inlet compartment) to the left of the baffles 21 and 22. This will cause the building up of a sufficient back pressure in the left or inlet compartments of the tubes 10 and 11 to smooth out the pulsations of the exhaust gas to the point where they do not make any objectionable noise and will also provide a sufficient internal pressure to insure a steady flow of gas into the outlet compartments of the muffler and prevent any inrush of air into the outlet pipe and the outlet compartments when the engine is decelerated and thereby substantially eliminate drumming when the volume of exhaust gas from the engine is suddenly diminished.

It is apparent that my construction is very simple and it may be very easily and cheaply produced. It comprises only two tubes, two end pieces which are simple stampings, two baffle pieces which are also simple stampings, and the inlet and outlet pipes. The end pieces and the baffles as positioned and secured insure a very rigid construction. There is no likelihood of any of the parts becoming loose and noisy.

What I claim is:

60 A muffler for an internal combustion engine, consisting of two tubes arranged in spaced concentric relation to each other, one of said tubes serving as the outer housing of the muffler, a pair of head pieces supporting the opposite ends of said tubes and forming 65 closures for the ends of said outer tube and

having central openings registering with the ends of said inner tube, a baffle plate secured in and intermediate the ends of said inner tube and separating the same into two unequal compartments, a second aperture baffle plate secured in and intermediate the ends of said outer tube and around said inner tube at a point adjacent the location of said first baffle plate, the inlet portion of said inner tube which is the longer portion having a group of lateral gas passages therein adjacent the entrance thereto and another group adjacent said baffle plate, and the outlet portion of said tube which is the shorter portion having lateral gas passages therein, the total area of such lateral gas passages in the inlet portion of said inner tube being greater than the total area of the lateral passages in the outlet portion thereof.

EDWARD H. RADECKY.
